SERVING TRAY FOR AUTOMOBILE SEATS

Riley H. Brooks, 1522 1st St.,
Webster City, Iowa 50595

Filed July 28, 1970, Ser. No. 24,187

Term of patent 14 years

Int. Cl. D7—07; D12—16

U.S. Cl. D87—1

Fig. 1

Fig. 2

Fig. 3

Fig. 4

Fig. 5

FIG. 1 is a frontal perspective view of a serving tray for automobile seats showing my new design;

FIG. 2 is a top plan view thereof shown at an enlarged scale;

FIG. 3 is a side elevational view thereof as seen from the left-hand side of FIG. 2;

FIG. 4 is a front elevational view thereof; and
FIG. 5 is a rear elevational view thereof.

I claim:

The ornamental design for a serving tray for automobile seats, as substantially shown.
